Attorney

UNITED STATES PATENT OFFICE.

HARRY H. SWARTZ, OF BELL, PENNSYLVANIA.

ROCK DRILL.

Application filed June 17, 1924, Serial No. 720,592. Renewed September 18, 1926.

This invention relates broadly to an improved rock drill, but it has more specific reference to a device which I have designed for supporting a pneumatic jack hammer in a convenient position for effective drilling.

Under ordinary circumstances when holes are drilled in rocks in mines and the like through the use of a common portable jack hammer, the same is held solely in the hand of the operator. The present invention embodies a device which serves to support the hammer so that the operator will be relieved of considerable strain and will be permitted to exert more force on maintaining the drill in engagement with the work.

The primary feature of the invention is the provision of a practical, simple and sturdy structure which is an improvement upon devices of this character heretofore used.

Other objects and advantages of this invention will become apparent from the following description and drawing.

In the accompanying drawing forming a part of the application and in which like numerals are employed to designate like parts throughout the same:

Figure 1 represents a side elevation of the improved device as constructed in accordance with the present invention.

Figure 2 is an enlarged detail section taken substantially on the plane of the line 2-2 of Figure 1.

In carrying out the invention I provide a suitably shaped and sized base 1 having supporting legs 2 which may, if desired, be provided with anti-slipping calks 3. Slidable at its lower end upon the upper side of the base is a supporting member or board 4.

In the present instance, the upper end of the board is provided with a notch forming a seat in which the body portion of a conventional pneumatic hammer H is received. With this arrangement it is obvious that by supporting a hammer on the board and holding the latter with the knee, the drill stem D can be more accurately guided and effectively maintained in engagement with the rock R. To assist in maintaining the drill in engagement with the rock, I use a flexible cable or the like 8 and attach this at one end to the hammer. The

intermediate portion thereof being passed over a guide pulley 9 on the upper end of a supporting rod 10 and there being a comparatively heavy weight 11 on the lower end of the cable for exerting a pull upon the hammer as is obvious. The rod 10 may be detachably connected to a socket or the like 12 which is secured to the upper side of that end of the base adjacent the rock.

As the method of using the improved device is undoubtedly obvious from the description and drawing, it is thought unnecessary to enter a more detailed description.

Having thus described the invention, what I claim is:

1. In a rock drill structure of the class described, a base adapted to rest on the ground, means for securely anchoring the base upon the ground, a drill supporting member having its lower end resting slidably upon the upper side of said base adapted to be manually shifted thereupon, said member being provided at its top with the seat in which the drill is adapted to be slidably received, and a rod rising from said base, and being of a height substantially equal to said supporting member, said rod being provided at its top with a guide, and a weighted cable adapted to be connected at one end to the drill and having its intermediate portion trained over said guide.

2. In a device of the class described, a base adapted to be supported upon the ground, anti-slipping and anchoring means carried by said base, a supporting member rising vertically from the upper side of said base, the lower end of said supporting member being detachably and slidably mounted upon said base, to permit it to be shifted thereon, the upper end of said member being provided with a notch forming a seat, in which the body of a drill is adapted to be slidably seated, a socket fastened to the upper side of said base opposite said supporting member, a rod connected to and rising from said socket, said rod being provided at its upper end with a pulley, and a cable passing over said pulley, said cable being adapted to be connected at its upper end to the drill, and a weight connected to the opposite end of said cable.

In testimony whereof I affix my signature.
HARRY H. SWARTZ.
